UNITED STATES PATENT OFFICE

131,270

DESIGN FOR A WINDOW VENTILATOR HOUSING

Viktor Schreckengost, Cleveland Heights, Ohio, assignor to The Murray-Ohio Manufacturing Company, Cleveland, Ohio, a corporation of Ohio

Application May 28, 1941, Serial No. 101,204

Term of patent 7 years

To all whom it may concern:

Be it known that I, Viktor Schreckengost, a citizen of the United States, residing at Cleveland Heights, county of Cuyahoga, and State of Ohio, have invented a new, original, and ornamental Design for a Window Ventilator Housing, of which the following is a specification, reference being had to the accompanying drawings, forming a part thereof.

Fig. 1 is a perspective view of a window ventilator housing, showing my new design; and

Fig. 2 is a front elevational view of a window ventilator housing, with the enclosing screen removed.

The bottom of the housing is substantially the same as the top of the housing, such top being clearly shown in Fig. 1 of the drawings.

I claim:

The ornamental design for a window ventilator housing, substantially as shown and described.

VIKTOR SCHRECKENGOST.
